UNITED STATES PATENT OFFICE.

HOWARD D. COLMAN, OF ROCKFORD, ILLINOIS, ASSIGNOR, BY MESNE ASSIGNMENTS,
TO HOWARD D. COLMAN, LUTHER L. MILLER, AND HARRY A. SEVERSON, COPART-
NERS AS BARBER-COLMAN COMPANY, OF ROCKFORD, ILLINOIS.

MECHANICAL MOVEMENT.

1,116,019.

Specification of Letters Patent.

Patented Nov. 3, 1914.

Substitute in part for application Serial No. 526,856, filed October 24, 1894. This application filed March 25, 1907. Serial No. 364,558.

To all whom it may concern:

Be it known that I, HOWARD D. COLMAN, a citizen of the United States, residing at Rockford, in the county of Winnebago and State of Illinois, have invented certain new and useful Improvements in Mechanical Movements, of which the following is a specification.

The invention herein shown relates to a means for feeding two members at different rates of speed by means acting directly upon one of said members.

In the drawings I have illustrated the invention in connection with a machine for drawing warp threads through the heddle eyes of loom harnesses and between the dents of a loom reed. Said machine comprises a carriage in which the harnesses are suspended and upon which the reed is loosely or slidably carried, said carriage being fed with relation to the drawing-in mechanisms by a device which positively feeds the reed. Owing to the difference in length of the harnesses and the reed, they would get out of proper relation if fed at the same rate through the machine.

The present invention, therefore, provides means for causing the harnesses to move more rapidly or more slowly than the reed, as may be desired.

In the accompanying drawings, Figure 1 is a perspective view of a portion of a warp-drawing machine embodying the features of my invention. Fig. 2 is a side elevation of some of the parts comprised in the present invention. Fig. 3 is a fragmental view of the carriage, illustrating the means for slidably supporting the reed. Fig. 4 is a detail view of the reed-feeding device.

Referring to the drawings, 1 indicates the carriage for the loom harnesses *a* and the loom reed *b*. Said carriage is provided with means for movably supporting it, comprising, in this instance, bearing rollers 2, only one of which is seen in the drawings, said bearing rollers running upon a track 3 fixed in the framework of the machine. For convenience, I will herein designate the end of the machine from which the carriage 1 starts the head end of the machine, and the opposite end the foot end of the machine.

The carriage 1 comprises two frame members 4 in which are formed two grooves 5 to receive the longitudinal side bars of the reed. Said reed is loosely held in the carriage 1 by means of catches 6 fixed upon a rock shaft 7, said rock shaft being operated by means of cranks 8.

Supported in any suitable way at the side of the track 3 is a rail 9 inclined at an angle with the track 3. In the present instance, I have shown the end of the rail 9 toward the starting position of the harness and reed carriage as being pivotally mounted at 10 upon the track 3, the opposite end of said rail being adjustably supported in a saddle 11 pivotally connected to the upper end of a screw 12. Said screw 12 extends through an opening 13 in a block 14 rigidly mounted in the machine frame. Nuts 15 on said screw at opposite sides of the block 14 provide means for reciprocating the screw and for locking it in position.

To one of the frame members of the carriage 1 is pivoted a bell-crank 16. One arm 17 of this bell-crank is pivotally connected with a rod 18 carrying at its lower end a roller 19 adapted to run upon the rail 9. The rod 18 is extensible in length, being made of two telescoping sections 18^a and 18^b arranged to be fixed in adjusted position by means of a set screw 20. A guide 21 fixed to the carriage 1 slidably embraces the rod 18. The other arm 22 of the bell-crank 16 is pivotally connected with a rod 23, against the opposite end of which the reed *b* is arranged to bear either directly or indirectly. In the present instance I have shown a spring-cushioning device 34 between said rod and said reed. The rod 23 is preferably guided by means of a screw 24 extending through an elongated guide slot 25 in said rod.

In the machine illustrated in the present drawings the reed *b* is moved by means of a feeding finger 26 adapted to enter between adjacent dents of the reed and push said reed through the machine. The feeding finger 26 is fixed to the upper end of an arm 27, said arm being fixed to a shaft 28 slidably and rotatably mounted in bearings 29 in the machine frame. To the shaft 28 is fixed an arm 30 adapted to engage the periphery of a cam 31 mounted on a

cam shaft 32 rotatably supported in the machine frame and driven by the belt 33, said cam being of a conformation designed to produce alternately an oscillation and a longitudinal movement of the shaft 28.

In operation, when the cam shaft 32 is rotated the arm 27 is first rocked toward the reed *b*, then moved toward the foot of the machine, then rocked away from the reed, and finally moved toward the head of the machine. The feeding finger 26 consequently is first inserted between two dents of the reed, then moved sidewise to force the reed toward the foot of the machine, then withdrawn from said reed, and finally returned to its initial position. The reed *b* is thus positively moved toward the front end of the machine by the feeding finger 26, the reed bearing against the end of the rod 23. Assuming the rail 9 to be in the position shown in Fig. 2, it will be seen that any movement communicated to the rod 23 by the reed *b* will be transmitted to the carriage 1 through the bell-crank 16. The free end of the arm 17 of said bell-crank being maintained at a constant height above the inclined rail 9, the force exerted upon the arm 22 of said bell-crank by the feeding finger 26 results in an oscillation as well as a bodily forward movement of said bell-crank. The forward movement of the pivotal center of said bell-crank produces a forward movement of the harness and reed carriage 1, and the oscillation of said bell-crank causes a difference in the rates of movement of the reed and the carriage. The forward movement of the pivotal center of the bell-crank 16, it will be observed, is greater than the forward movement of the free end of the arm 22 of said bell-crank when the rail 9 is inclined upwardly toward the foot of the machine, resulting in a relative movement between the harness and reed carriage 1 and the reed *b*, said reed slipping in the grooves 5. The rail 9 is adjusted to such an angle that the difference in the rates of travel of the harnesses and the reed will be sufficient to compensate for the unequal spread of said reed and said harnesses. When the rail 9 is inclined downwardly toward the foot of the machine, the harnesses will move more slowly than the reed.

It will be understood that any suitable means may be employed for moving the reed, and that said reed may be supported upon the harness and reed carriage in other positions and through the agencies of other devices than those herein shown.

It will also be apparent that the differential feed mechanism of this invention may

be used in other classes of machines than the one herein described.

I claim as my invention:

1. In a mechanical movement, in combination, a track, a carriage mounted on said track, a member carried by said carriage; means for positively moving said member; a member pivoted to said carriage and connected with said positively-moving member; and a rail extending in a vertical plane parallel with the vertical plane of said track, said rail extending at an angle to said track, which rail supports a portion of the pivoted member, whereby movement imparted to the member carried by the carriage causes a differential movement of said last mentioned member and said carriage.

2. The combination of a harness and reed carriage in which a reed may be loosely supported, means for supporting said carriage for rectilinear movement, a lever pivoted on said carriage, against one arm of which lever the reed is arranged to press, means slidably engaging the other arm of said lever to resist the pressure of the reed, said lever-engaging means extending at an angle to the carriage-supporting means, and reed-engaging means to move the reed against the lever, whereby differential movement is imparted to the reed and the harness carriage.

3. The combination of a harness and reed carriage in which a reed may be loosely supported, means for supporting the carriage for rectilinear movement, a lever pivoted on the carriage against one arm of which lever the reed is arranged to press, an adjustably inclinable way extending along said supporting means, the other arm of said lever supported by said way, and reed-engaging means to move the reed against the lever whereby differential movement is imparted to the reed and the harness carriage.

4. In a mechanical movement, the combination, of a track; a carriage mounted on said track; a member slidably carried by said carriage; means for positively moving said member; a member pivoted to said carriage, said positively moving member connected to said pivoted member above said pivot; and a rail extending in a direction different from that of said track, but in a vertical plane parallel with said track, said rail supporting a part of said pivoted member.

HOWARD D. OLMAN.
